CARBURETOR HAVING A VACUUM REGULATED
METERING ROD

Juris Berzlapa, St. Louis, Mo., assignor to ACF Industries, Incorporated, New York, N.Y., a corporation of New Jersey

Filed Dec. 1, 1965, Ser. No. 510,811
6 Claims. (Cl. 261—60)

This invention relates to a carburetor. It relates in particular to a carburetor utilizing a controlled metering rod for more accurately regulating flow of fuel to the carburetor mixing conduit.

In carburetors of the type contemplated, the flow of fuel passing from the carburetor fuel bowl to the mixing conduit is regulated to some extent by a metering rod positioned in an orifice connecting the source of fuel with the mixing conduit. The primary function served by a metering rod is to afford the carburetor a higher degree of efficiency and full economy. Ideally, the metering rod formed end is so contoured to provide an optimum flow of fuel to the mixture conduit under all engine operating conditions. This, however, is not always possible. Particularly at low and idle speeds, regulation of the metering rod to obtain a proper air fuel mixture becomes difficult. For example, the degree of vacuum at the engine intake manifold will vary within the range of about 25 inches of mercury to about a few inches of water. Engine loading and speed will of course be reflected in the vacuum condition at the intake manifold. Thus, with respect to the operation of an ordinary metering rod responsive to engine vacuum, the rod will be adjusted an amount directly proportional to the degree of engine vacuum.

Fuel control is achieved by regulating the position of the metering rod in an orifice to alter the flow of fuel passing into the carburetor discharge nozzle as the demand for fuel is varied by the engine. One such regulating means successfully utilized, includes a pneumatic or air motor arrangement connected to a source of vacuum such as the engine intake manifold, whereby variations in manifold vacuum are reflected in a comparable adjustment in the metering rod position.

It has been found that while the fuel metering rod above described is beneficial in many respects to carburetor operation, under some circumstances it is desirable that closer fuel control be exercised to improve engine combustion. Further, where an air motor actuator is utilized, an inadequate reaction rate is present between the need for a richer air-fuel mixture, and the delivery of sufficient fuel to provide such a mixture is often excessive. This follows since the normal air motor and metering rod arrangement is designed to respond proportionately to the degree of manifold vacuum and consequently, in the usual instance of engine operation, intake manifold vacuum varies directly with engine speed and load. Thus, when a sudden demand for greater engine power occurs, the proper amount of fuel to mix with incoming air is unavailable.

Also, it has been found that under certain engine speeds and loads, excessive fuel delivery to the discharge nozzle results in an over-rich air fuel mixture and the creation of undesirable amounts of unburned hydrocarbons which discharge to the atmosphere with engine exhaust fumes. Engine operation under such circumstances is not only uneconomical, it tends to aggravate the frequent problem of air pollution due to the emission of unburned hydrocarbons and other undesirable matter into the atmosphere.

It is therefore an object of the invention to provide an improved carburetor including a fuel metering device

2

to accurately and economically furnish a proper air fuel mixture to the engine under all operating conditions. A further object is to provide a carburetor of the type described including a fuel system adapted to assure optimum air fuel mixtures at load speeds as well as at idle speed. A still further object is to provide a fuel metering system for a carburetor including an automatically adjustable metering rod. Still another object is to provide an air motor regulated fuel metering rod so arranged to instantaneously respond to engine conditions, said motion giving a stepped-up performance particularly at low engine speeds.

The foregoing objects, together with others not specifically enumerated will be clear to those skilled in the art from the following description.

The invention as herein disclosed is directed to a well-known carburetor construction utilizing a fuel metering rod cooperative with an orifice or jet formed in the base of the carburetor fuel well, the latter which forms a portion of the carburetor body. The well portion of the body is disposed within the carburetor fuel bowl. The metering rod is arranged such that the tapered or metering end is operatively positioned within the fuel metering jet to define a variable annulus.

The upper end of the metering rod is retained in an air motor assembly responsive to manifold vacuum. Thus, the metering rod is connected to a displaceable diaphragm in the air motor which adjusts automatically in response to variations in engine manifold, which normally reflects engine speed and load. However, to avoid the normal reaction of the air motor to over-adjustment at low engine speeds, which would provide an over-rich air fuel mixture, and to assure an adequately rich fuel mixture as needed, means is provided for minimizing or overcoming the effects of intake manifold vacuum on the air motor by at least partially spoiling the vacuum as the throttle is advanced from engine idle position.

The invention is presently illustrated and described as incorporated into the body of a single barrel carburetor similar to the model shown in U.S.P. 3,189,331. It is understood however, that the following description of the fuel metering device is for the purpose of illustrating a particular structure which may be applied equally as well to other forms of carburetors such as multi-barrel units and the like.

Referring to FIGURES 1 and 2, the carburetor consists essentially of a casting 10, which is formed with a fuel and air mixture conduit 12, and a fuel bowl cover portion 14 from which depends an accelerating pump cylinder 16, an accelerating fuel passage 18, and a fuel well structure 20. Mixture conduit 12 is connected by a flange 13 to intake manifold M of an internal combustion engine E. In the lower part of the conduit 12 there is rotatably mounted a throttle valve 22 fixed to a throttle shaft 24 journaled in appropriately aligned apertures in body casting 10. In the upper portion of the fuel air mixture conduit 12 there is similarly mounted for rotational movement an unbalanced choke valve 26 fixed to a choke valve shaft 28, which is also journaled in aligned apertures through the body casting 10.

The top of mixture conduit 12 is connected to an air filter 29, partially shown in cross-section in FIGURE 2. Between the upper and lower portions of mixture conduit 12 is formed a venturi or air flow restricting surface portion 30. A small booster venturi 32 is formed integrally with body casting 10 and has an inner venturi surface 34 coaxially aligned with the mixture conduit 12 and the primary venturi surface 30.

A fuel bowl 36 is fixed beneath fuel bowl cover 14 and is held with its rim against a gasket 38 fitted between the rim of the fuel bowl 36 and matching portions of the fuel bowl cover 14. A float structure 40 is pivotally

mounted from pin 42 journaled in a depending portion of fuel bowl cover 14. A lever arm of float lever 43 fixed to float 40 abuts the lower end of a needle valve 44 having an upper tapered end extending into a valve seat 46 of the inlet 47 to the fuel bowl 36.

Fuel is forced under pressure by pump 50 from the fuel tank 15 through fuel line 19 and to carburetor inlet 47. When fuel level in bowl 36 is low, float 40 drops commensurably and lever arm 43 permits valve 44 to be displaced to an open position under fuel pressure. Fuel then flows into bowl 36 until reaching a predetermined level. Needle valve 44 is closed by the upward urging of float lever 43 as the fuel level rises.

Referring to FIGURES 3, 4, and 5, the lower end of fuel well 20 is closed by a threaded fitting 56 having a central orifice 69 which is formed to provide the metering jet for the flow of fuel from fuel bowl 36 to mixture conduit 12. A screw driver slot 57 is provided in the lower side of fitting 56 to permit removal. The upper end of fuel well 20 intersects fuel passage 58 directed downwardly into secondary venturi 32. A nozzle fitting 60 is held in the end of passage 58, one end of the fitting 60 extending into the secondary venturi 52. A fuel emission tube 62 is fitted and supported within well 20.

Metering rod 66 is suspended within fuel well 20, having a metering end 68 formed with varying diameters. The formed end 68 is positioned within the main fuel jet orifice 69 for operation in response to engine requirements. Flow of fuel through main orifice 69 is controlled by metering rod 66 and in accordance with that portion of the formed end 68 which is positioned within opening 69.

Metering rod 66 is accurately contoured at lower end 68 in fuel orifice 69 to permit maximum fuel efficiency. In particular, with the engine running at idle, the lower cylindrical end 55 of metering rod 66 fits closely with adjoining walls of orifice 69, thereby defining a minimum annulus to form a sufficiently large fuel passage to sustain the engine at idle. This arrangement permits satisfactory and economical engine operation without overenrichment of the fuel mixture, a condition that promotes improved utilization of fuel energy.

Referring to FIGURES 3, 4, and 5 fuel well 20 includes a relatively narrow elongated channel formed substantially uprightly in the carburetor wall and opening at the upper end into an enlarged bore 48 along an outwardly tapered surface 49. Peripheral shoulder 51 formed on tapered surface 49 provides a rigid annular seat for flexible diaphragm 52 which is displaceable to inner and outer positions.

The air motor for actuating metering rod 66 includes basically a sealed plenum chamber 95 formed in bore 48 and having an inlet communicating said chamber to the engine intake manifold M. As shown in FIGURE 3, plenum chamber 95 is formed in fuel bowl cover 14 including a passage 71 which in turn is connected to passage 72 in the wall of casting 10. Passage 72 extends downwardly terminating at the lower face of casting 10, and is provided with a constricted portion 73 which may be a small bore insert, press fitted into passage 72. The size of passage 73 is determined or calibrated in accordance with a specific carburetor and motor characteristic. The function of passage 73 is to regulate air flow between intake manifold M and passage 72. However, the open area of said passage 73 is also determined by, and is coordinated with the size of passage 74 as will be hereinafter noted.

A second passage means 74 likewise formed in a wall of casting 10 defines a calibrated limited flow duct which may include an orifice, or merely be constricted in its entirety to meter air flow therethrough. Second passage means 74 terminates at a port 76 opening into mixture conduit 12. Port 76 is so positioned in a wall of mixture conduit 12, and with respect to throttle valve 22, as to be either substantially blocked when the throttle is in idle

position or to be slightly downstream of the throttle plate edge. However, preferably the lower peripheral edge of plate 22 is contiguous with the upper edge of port 76. Operationally, when the throttle plate is adjusted slightly from idle position as shown in FIGURE 7, port 76 will be disposed on the throttle upstream side and consequently exposed to substantially atmospheric pressure. Otherwise, at throttle idle, passages 73 and 76 are simultaneously exposed to intake manifold vacuum.

Referring to FIGURES 4 and 5, the structure of the air motor comprises essentially diaphragm 52 having a peripheral edge urged into sealing contact with shoulder 51. Diaphragm 52 is centrally positioned on hub 59 and held in abutment with shoulder 54 by a cup-like member 78, being downwardly biased by spring 77.

A spring retainer 79 includes a peripheral lip 81 urged into contact with diaphragm 52, said retainer being compressibly held by a sealing cover member 82 having a flange 83 frictionally retained in the opening of bore 48 by a washer 87. One or more openings 86 are formed in the wall of spring retainer 79. A depression at the center of cover 82 provides an abutment for the upper end of metering rod head 53 thereby limiting upward movement of the rod to locate tapered end 55 in idle position within orifice 69.

Operation of the above-described device is best understood with reference to FIGURES 6 and 7 and the graph of FIGURE 8. With the engine operating at idle speed, throttle plate 22 will be positioned as shown in FIGURE 6 with the peripheral edge in engagement with, or contiguous with the adjacent wall of mixing conduit 12. Said throttle edge as shown particularly in FIGURE 6 is disposed immediately above port 76, or alternatively in such position as to define a closure to port 76 thereby impeding or preferably precluding flow of air through said port. Thus, with the engine idling, a manifold depression of approximately 19 inches of mercury will be established in the intake manifold and communicated through constricted passage 72, passage 71 and openings 86 to plenum 95 in bore 48. The vacuum in said plenum is sufficient to overcome the downward biasing action of spring 77 thus withdrawing diaphragm 52 to its maximum upward position. Cylindrical end 55 is therefore disposed within orifice 69 to provide an optimum opening for fuel flow to the nozzle 60. As previously noted, this fuel flow is calibrated to most efficiently maintain the engine at idle speed by virtue of the accurately formed annulus between rod end 55 and the adjacent walls of orifice 69.

Thus, at engine idle, diaphragm 52 will remain as shown in FIGURE 4, completely withdrawn to its upper maximum. Head 53 is thus disposed in abutment with depression 83 thereby maintaining the location of cylindrical portion 55, in orifice 69. This is illustrated by line A-B in the graph of FIGURE 8.

Normally, in an air motor controlled metering rod not embodying the invention, as the throttle plate is displaced from idle position to provide additional power to the engine, the intake manifold depression will be depressed. The effect communicated to the plenum chamber is that the withdrawing force on diaphragm 52 is lessened and consequently the diaphragm will be displaced slightly downward by the biasing of spring 77 to move the metering rod further into the orifice 69 thereby providing a greater annulus for fuel flow. In this type arrangement, however, the additional fuel afforded is insufficient to properly maintain engine speed.

In accordance with the disclosed arrangement and again referring to FIGURE 7, as throttle plate 22 is displaced downwardly from idle position to provide a greater flow passage in mixture conduit 12, the periphery of plate 22 will sweep past port 76 thereby disposing the latter upstream of the throttle plate. Passage 72 is now communicated instantaneously by way of passage 74 with atmosphere thereby in effect collapsing or reducing the

vacuum in the plenum chamber. Diaphragm 52 is now urged immediately downward by spring 77 to position constricted end 68 of rod 66 in orifice 69 thereby increasing the annulus opening between the metering rod tapered end, and the orifice 69 to provide an optimum fuel flow or slightly richer air fuel mixture.

Again regarding operation of the carburetor, referring to FIGURE 8, instantaneous depression or falling of the air motor vacuum is illustrated by the family of curves B-C, B-C1, B-C2, and B-C3. The abrupt step down in the curve from a substantially constant slope as at AB, to a curve characterized by a sharp break in "air motor vacuum" at a point just past engine curb idle. This is represented by a substantially vertical segment of the curve terminating at C.

Thereafter, for further decreases in "intake manifold vacuum," the comparable decrease in air motor vacuum will be relatively minor exemplary of which is by curve C', and D' having a substantial portion thereof representing a constant air motor vacuum for a period of intake manifold vacuum decrease.

While the graphical representation of FIGURE 8 depicts a number of curves adapted to different carburetors, the common characteristic of each curve is the abrupt step down defined between points B, C, and D as contrasted with the relatively constant slope typical of the vacuum relationship between the air motor and the intake manifold, where the present invention is not utilized.

It is clear from the foregoing that the carburetor presently described affords several advantages heretofore unrealized in the art. For one thing, a more accurate and closely controlled metering of fuel to the discharge nozzle assures a more economical utilization of the fuel energy at all engine speeds. Further, and by no means secondly in importance, is the minimization or complete elimination of undesirable hydrocarbon emissions which would tend to aggravate a smog problem. Also, the novel arrangement permits automatic adjustment of the carburetor air fuel mixture calibration in immediate response to a particular demand or requirement such as a minor load imposed on the engine in response to a variation in intake manifold vacuum.

The structure as herein described may be varied slightly by the addition of springs and the like to supplement the action of the air motor. However, successful operation of the carburetor in the manner contemplated will depend primarily on the relative size of the respective passages 73 and 74 which are designed to impede air flow both to and from the air motor thereby controlling fuel feed to the engine.

It is appreciated by those skilled in the art that the foregoing invention embodies an improvement in carburetors not heretofore known or practical. More specifically, the desirable features of an air motor controlled metering rod are utilized to the fullest. However, under predetermined conditions, the function of the air motor is in effect by-passed by the spoiling of air motor vacuum in order that the metering rod might be utilized more advantageously.

It is further appreciated that the foregoing description is designed for application to a variety of basic carburetor structures. It is therefore seen that the unique arrangement can be modified and changed, without departing from the spirit and scope of the invention.

I claim:

1. In a carburetor for an internal combustion engine having an intake manifold including; a body, a mixture conduit formed in the body, a throttle valve including a throttle plate carried on a throttle shaft, the latter being

journalled in the mixture conduit and being operable to regulate the passage of air and fuel mixture therethrough, a fuel bowl formed in said body holding a supply of fuel, a venturi in said body including a nozzle opening therein, a duct carrying a fuel stream from said fuel bowl to said nozzle for injecting fuel into said mixture conduit, a metering orifice in said fuel duct adapted to regulate the flow rate of said fuel stream, an air motor associated with said carburetor and having a first passage means connected to a source of varying vacuum in said engine, said air motor having a displaceable diaphragm at one wall thereof moveable between inner and outer positions in response to variations in said engine vacuum, said metering rod having opposed ends, one of said ends being disposed in said metering orifice, the other rod end engaging said diaphragm to reciprocate said rod between said inner and outer positions in said orifice in response to a vacuum change in said air motor, the improvement therein of; means forming a second passage in communication with said air motor and having a port opening into said mixture conduit, said throttle plate being moveable in said mixture conduit between open and closed positions to regulate the speed of said engine, and said throttle when positioned in the closed position in the mixture conduit providing a sufficient passage for air fuel mixture to maintain an engine at idle speed and said throttle plate when in said closed position having an edge disposed immediately below said port opening into said mixture conduit, to prevent air flow through the latter, and when said throttle plate is displaced slightly from said closed position, said port will be positioned upstream of said throttle plate edge to permit a metered flow of air through said second passage and into said first passage, whereby the degree of vacuum imposed on said diaphragm for urging said metering rod into the inner position is instantaneously lessened thus permitting the air motor to instantaneously actuate the metering rod a predetermined distance toward the outer position to instantaneously form a greater fuel passage with the metering orifice to provide an increased fuel flow to said mixture conduit.

2. In a carburetor as defined in claim 1 wherein said first passage means communicates said air motor with the intake manifold of said engine.

3. In a carburetor as defined in claim 2 wherein said first passage means includes a constricted portion defining a limited opening for passage of air therethrough.

4. In a carburetor as defined in claim 1 wherein said means forming a first passage includes a channel formed in the wall of said carburetor body and having a constriction therein to limit air flow therethrough.

5. In a carburetor as defined in claim 1 wherein, when said throttle plate is in the closed position, said edge of said throttle plate will be positioned contiguous with the lower edge of said port opening into said mixture conduit.

6. In a carburetor as defined in claim 1 wherein said air motor includes biasing means normally urging said diaphragm outwardly from the air motor.
